CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

SPRING AIR-GUN.

1,180,855.

Specification of Letters Patent. Patented Apr. 25, 1916.

Application filed June 15, 1914. Serial No. 845,283.

To all whom it may concern:

Be it known that I, CHARLES F. LEFEVER, a citizen of the United States of America, residing at Plymouth, in the county of 5 Wayne and State of Michigan, have invented certain new and useful Improvements in Spring Air-Guns, of which the following is a specification, reference being had therein to the accompanying drawings.

10 The invention relates to spring air guns of the type in which the spring is tensioned by a mechanism simulating the so-called pump guns.

It is the object of the present invention 15 to simplify the construction of the spring-compression mechanism, and to this end the invention comprises, first, the construction in which the rearward movement of the actuating handle causes the compression of 20 the spring against the plunger abutment, while the forward movement of said handle moves the plunger and compressed spring rearward to the firing position.

The invention also has reference to the 25 construction of sear and trigger locking mechanism, and further to various details of construction as hereinafter set forth:

In the drawings:—Figure 1 is a side elevation of the gun; Fig. 2 is a longitudinal 30 section thereof when the spring is released; Fig. 3 is a similar view showing the operation of compressing and retracting the spring; Figs. 4, 5 and 6 are perspective views respectively of the false barrel, the frame 35 and the lever mechanism; and Fig. 7 is a section similar to Figs. 2 and 3 showing the spring compressed and in firing position. Fig. 8 is a detail cross section taken through the lever handle. Fig. 9 is a detail perspective view of a locking member or dog. Fig. 10 is a detail perspective view of the trigger.

A is the false barrel of the gun within 45 which the true or firing barrel (not shown) is located.

B is the actuating member or pump handle for the spring compression mechanism. This is slidably secured to the false barrel by attaching to the latter a longitudinally-extending strip C having projecting lips C' which are embraced by a U-shaped guide member D secured to the handle. This guide member is preferably struck-up from sheet metal and is provided with ears D' at

55 opposite ends which embrace the wooden handle B.

E is a shank member having a shouldered head E' at one end and a body portion of reduced diameter which passes through apertures in the ears D' and an alined aperture in the handle B, while its opposite end is provided with clenched flanges E² for retaining it from displacement.

F is the frame member which is struck up from sheet metal to form parallel sides 65 with a rounded top portion F' and a flat bottom portion F². The under side of this member is slotted at F³ to receive the depending flanges A' of the barrel A, which flanges form a fulcrum support and guide 70 for the lever mechanism. The frame member F is further provided with a trigger guard G, the forward end of which is embraced by the flanges A' and secured there- 75 to by a rivet G'.

To secure the barrel A to the frame F, the two parts are telescopically engaged until apertures F⁴ in the member F are registered with apertures A² in the flanges A'. A cross pin H is then inserted, which will 80 lock these two parts together, and to prevent any looseness or rattling, the rearward end of the barrel is provided with a tapering or wedge shaped portion A³ which engages a cross pin H' at the rear end of the 85 frame.

I is the plunger which slidably engages a portion of the barrel A in rear of the abutment J.

K is a spring for actuating the plunger 90 I, which is sleeved about a shank I' of said plunger, having a tapering point I² with a shoulder I³ adjacent thereto.

L is a movable abutment slidable within 95 the barrel A and operated by the break-joint levers M M', which in turn are secured to and operated by the handle B. The lever M is fulcrumed upon a cross pin N engag- 100 ing apertures N' in the flanges A'. The general form of the lever M is that of a bell-crank, which is pivotally connected at its free end with the sliding abutment L through the medium of a pivotal link O. The levers M and M' and the link O will 105 preferably be made of sheet metal, bifurcated in form. The sliding abutment L is hollow, and within the same is arranged the sear P, which is in the form of a lever piv-

oted upon the pin P' which also forms the connection for the link O . The forward end of the lever P has a hook P^2 for engaging with the shoulder I^3 on the shank I' , while the rear end of said lever extends on the opposite side of the fulcrum to a point for engagement with the trigger Q . There is also provided a spring P^3 which at one end engages a notch in the lever P and at its opposite end abuts against the link O . The arrangement is such that whenever the handle B is drawn backward along the guide C the levers M and M' will be bent downward, and the lever M through the medium of the link O will force the sliding abutment L forward, compressing the spring K and carrying the sear P to a position where the hook P^2 will engage with the shoulder I^3 of the shank I' . The spring P^3 will hold the hook in this engagement, and thus the abutment L will be held in fixed relation to the plunger, the spring being compressed therebetween. This will permit of a movement of the plunger, spring and abutment rearward by the forward movement of the handle B until the levers M and M' are straightened and the rear end of the sear lever comes into operative relation to the trigger Q .

During the operation of compressing the spring the sear being withdrawn from the trigger is out of the influence of the latter, so that when the hook P^2 engages with the shoulder I^3 , these parts cannot be disengaged until the levers are returned to their normal position. To prevent any premature disengagement after the sear has come into proximity to the trigger, the latter is locked during the whole lever movement and is only released at the completion of the return movement. To accomplish this, the trigger Q is provided with a locking member R which is in the form of a dog pivoted on the pin H' , the free end of said dog being engageable with a notch Q' in the trigger.

R' is a spring which engages with the dog R to force the same into a position for engaging with the notch Q' , but when the parts are in normal position, the rearwardly-projecting end P^4 of the sear lever P bears against the dog R and forces it rearward against the tension of the spring R' , so as to disengage from the notch Q' . In this position the trigger may be pulled, and when rocked will force the arm P^4 upward, depressing the forward end of the lever and disengaging the hook P^2 from the shoulder I^3 , which will release the shank I' and permit the forward actuation of the plunger by the tension of the spring. A cam portion Q^3 on the trigger serves to guide the dog R into engagement with the notch Q' , and also to force the dog out of the path when the trigger is pulled.

To cheapen the cost of manufacture, most of the parts, including the trigger and its locking dog R , are formed up from sheet metal stampings, which are inexpensive to manufacture and are of less weight than if made from solid metal.

What I claim as my invention is:—

1. In an air gun, the combination of a barrel member and a frame member both formed from sheet metal, the rear end of the barrel member being provided with a tapering bearing, a pin engaging registering apertures in said barrel and frame for securing the same together, and a second pin engaging said tapering bearing for holding the parts from rattling.

2. In a gun, the combination of a barrel member having depending parallel flanges formed on its rear end portion at each side of an opening in said portion, a frame member inclosing said end portion slotted to receive said flanges, and a cross pin engaging registering apertures in said frame member and the flanges of said barrel member to lock the parts in engagement.

3. In a gun, the combination with a barrel member and frame member having a telescopic engagement, of a spring-compression lever, depending parallel flanges on said barrel member engaging a slot in said frame member and embracing the said lever, and a fulcrum for said lever engaging said flanges.

4. In a gun, a frame member struck-up from sheet metal and having formed on its upper side a rounded bearing for the barrel, a barrel member telescopically engaging said frame member having a tapering bearing at its rear end and provided with depending parallel flanges for engaging a slot in said frame member, a trigger guard member secured to said frame member, embraced by and secured to said depending flanges on the barrel member, a spring-compression member having a fulcrum bearing on said depending flanges, a pin for securing said barrel member to said frame member, and a second pin engaging the tapering end bearing on said barrel member to hold the parts from rattling.

5. In a gun, the combination with the barrel, the plunger therein and the spring for actuating said plunger, of a slidabale abutment for said spring, a lever for moving said abutment forward to compress said spring, a swinging link actuating the abutment from the lever; a shank on said plunger projecting axially of said spring, a sear mounted on said slidabale abutment for engaging with said shank when said spring is compressed and a sliding handle for actuating said lever.

6. In a gun, the combination with the barrel having a fixed abutment therein, of a plunger, a spring for actuating the same, a slidabale abutment for compressing said

spring, a shank for said plunger extending axially of said spring, a sear on said slidable abutment for engaging said shank to lock said sliding abutment in fixed relation thereto, a lever for moving said sliding abutment forward and for returning the same, a trigger for releasing said sear, and locking mechanism for said trigger released by said sear at the completion of the movement thereof.

7. In a gun, the combination of a barrel, a fixed abutment therein, a plunger, a spring, a plunger shank extending axially of said spring, a slidable abutment, a sear mounted on said slidable abutment in the form of a lever having a hooked end for engaging a detent on said shank, the opposite end of said lever extending rearward of its fulcrum, a trigger for laterally deflecting the rear end of said lever to release the sear, and a locking dog for holding said trigger from movement, disengaged therefrom by the end of said lever upon the completion of the return movement of said slidable abutment.

8. In a gun, the combination with a plunger, of a shank extending rearward therefrom having a locking shoulder adjacent to its rear end, a tubular slidable abutment for compressing said spring about said shank, and a sear pivoted on said abutment in the form of a lever terminating at its forward end in a hook adjacent the front end of the abutment, and projecting exterior to the abutment to the rear of its pivot, and a trigger for engaging said rear end in the return position of said abutment to disengage said hook and release said spring.

9. In a gun, the combination with a barrel, of a slidable hollow abutment therein, a plunger having a shank for extending into said hollow abutment, a sear mounted on said abutment and having a rearwardly-extending arm, and a bifurcated lever for actuating said abutment, embracing the rearwardly-extending arm of said sear.

10. In a gun, a slidable abutment, a lever for actuating the same, a sear carried by said slidable abutment, a trigger for releasing said sear, and a lock for said trigger released by said sear.

11. In a gun, a hollow slidable abutment, a bifurcated lever for actuating said abutment, a bifurcated link for connecting said bifurcated lever with said abutment, a sear mounted within said hollow abutment embraced by said bifurcated link and having a rearwardly-extending arm embraced by said bifurcated lever, and a trigger for engaging said rearwardly-extending arm to release said sear.

12. In a spring gun, a plunger having a rearwardly-extending round shank terminating in a tapering nose with a shoulder adjacent thereto, a spring surrounding said

shank, a hollow abutment for compressing said spring, into which the tapering nose of said shank projects, and a sear mounted within said hollow abutment and movable therewith for engaging said shoulder to hold said spring compressed, the top of the abutment forming a stop limiting return motion of the sear.

13. In a spring gun, a slidable abutment, a sear mounted on said abutment and having a rearwardly-extending arm, a trigger mounted in fixed position adapted to laterally deflect said arm when in proximity thereto, and a dog for locking said trigger from movement when said arm is withdrawn and released by said arm when returned.

14. In a gun, the combination with a barrel, of a guide strip secured thereto and having laterally-extending lip flanges, a slidable lever handle, and a U-shaped guide on said handle embracing said lip flanges and having its end portions embracing the respective ends of the handle.

15. In a gun, a lever actuating handle, comprising a body portion, a guide member of U-shaped section extending longitudinally of said body portion and having ears for embracing the ends thereof, and a shank portion for attachment to the lever passing through aligned apertures in said ears and in said body portion and clenched at its opposite end.

16. In a gun, a lever folded from sheet metal to form bifurcated, inwardly-extending arms, a hollow slidable abutment actuated by said lever, a link connection between said inwardly-extending arms and said hollow slidable abutment, a pin for pivotally connecting said link with said abutment, a sear in the form of a lever embraced by said link and fulcrumed upon said pin, the rear end of said lever being embraced by said bifurcated inwardly-extending arms, and a trigger for laterally deflecting the inwardly-extending portion of said lever to release the sear.

17. In a gun, the combination with a barrel, an abutment slidable therein, a lever for sliding said abutment, a swinging link for actuating the abutment from the lever, a sear carried by the abutment, and a spring compressed between the sear and said swinging link to maintain the sear in its normal position.

18. In a spring gun, a slidable abutment, means for actuating the same, a sear carried by said abutment, a trigger for releasing the sear, and means for locking the trigger, engaging the same as the abutment moves forwardly and releasing the same as the abutment completes its return motion.

19. In a spring gun, a trigger, a sear actuated by said trigger, and a member for engaging the trigger when the sear is dis-

placed from firing position, the trigger having a cam portion for guiding the locking member into its locking position.

20. In a spring gun, the combination with 5 the frame and barrel thereof, of a plunger, a spring acting on the plunger, a sliding abutment for said spring, a slidable lever handle, a bell-crank lever pivoted upon the frame, a swinging link between one arm of

the bell-crank and the abutment, and a 10 swinging link between the other arm of the bell-crank and the slidable handle.

In testimony whereof I affix my signature in presence of two witnesses.

CHARLES F. LEFEVER.
